MAGNETIC CONVEYER

Homer D. Merrill, Berkeley, Calif.

Application October 28, 1947, Serial No. 782,479

3 Claims. (Cl. 198—41)

1

This invention relates to conveyors and particularly to conveyor carriages utilizing permanent magnets to support and carry articles of magnetizable (usually ferrous) materials.

Carriers using magnetism to support and hold articles of a magnetizable nature have a number of advantages. One of these is the ability to hold the article without marring the metallic surface or the finish which has been applied thereto. The usual articles of this type with which I am familiar, however, have employed electro-magnets. In the operation of an endless conveyor system these electro-magnets will be energized during such portion of the conveyor travel as it is desired to support the articles and deenergized at the point where the articles are to be released. There are a number of objections to these arrangements; for one, the current required is an item of expense; for another, the switching contacts are liable to get out of order, which may result in dropping the articles conveyed or alternatively, failure to release at the proper point. Current failure, of course, renders the entire device inoperative. In certain specific applications for example, the use of such a conveyor in spray painting with volatile and inflammable solvents, there is encountered the special problem of avoiding sparking of the contacts with the attendant danger from fire or explosion.

The present invention avoids all of these above-mentioned difficulties encountered in electro-magnetic systems by the use of permanent magnets with either a mechanical or magnetic means to release the hold of the magnets on the articles carried.

An object of my invention is to provide a magnetic conveyor carriage which is free from the objectionable characteristics of electro-magnetic carriages, but retains the advantages inherent in the use of magnets.

Another object is to provide an efficient and mechanically sound magnetic conveyor for articles which will release the articles at the desired point, and not before.

Other objectives of the invention will appear in the course of the following description, as well as their attainment.

In the drawings,

Figure 1 is a plan of a complete carriage having a magnetic release.

Figure 2 is an elevation of the carriage shown in Figure 1.

Figure 3 is an end elevation taken from the left in Figure 1.

2

Figure 4 is a plan of a carriage having mechanical release means.

Figure 5 is a side elevation of the carriage shown in plan in Figure 4.

Figure 6 is a section along line 6—6 of Figure 4.

Figure 7 is a section on the line 7—7, Figure 4.

Referring first to the device shown in Figures 1, 2 and 3, the carriage is referred to generally by the numeral 10. A hanger 11 and rollers 12 support the carriage for movement along a track 13, said movement being imparted by a chain indicated at 14.

15 The means for holding the article, which is in this instance a rather large flat-bottomed steel pan, comprises the plurality (6) of horseshoe magnets 15 secured to the framework of the carriage 10. The poles of the magnets are 20 in a common plane, though to hold other articles they may be differently located to suit the shape of the article.

25 Pivoted to the framework by means of journals 16 on each side of the carriage are magnet holders 17, shown best in Figure 3. Each holder includes a lever arm 18 upon which is mounted a roller 19. Secured to the holder 17 there are plurality of releasing or short-circuiting magnets 20 numerically equal to and cooperating 30 with the holding magnets. As indicated in full lines in Figure 3 the normal position of the releasing magnets is out of contact with the holding magnets. At the point along the main track of the conveyor at which it is desired to release 35 the article, there are provided on each side of the main track auxiliary tracks 21 so located and disposed as to cause the levers 18 to assume the position indicated in dotted lines of Figure 3 of the magnet holder 17. Springs, not shown, may 40 be used to keep the rollers 19 in contact with the tracks 21.

45 The magnets hold the iron or other magnetizable material articles by the passage of the lines of force between the two poles of each magnet through the material of the article. When the releasing magnets are in the position indicated in dotted lines of Figure 3, unlike poles together, lines of force are in effect short-circuited within the two magnets and the attraction of the 50 holding magnets for the articles is reduced to such degree that the weight cannot be supported.

Instead of being of substantially the same strength as the holding magnets 15, the releasing or short-circuiting magnets 20 may be sub-

stantially stronger. Where this is the case, when the short-circuiting magnets are brought into contact with the holding magnets, the reversed poles will react with a temporary residual magnetism in the article so that the article is not merely released but is positively rejected.

In the embodiment of the invention illustrated in Figures 4 through 7, the carriage is indicated generally by the reference numeral 30. This carriage is supported by the hanger 31 and rollers 32 on the track 33 and is moved along the track by a chain which is not shown but which is similar to chain 14 in Figures 1, 2 and 3.

The holding means in this embodiment comprises a plurality of bar magnets 34, all oriented alike as regards their north and south poles. Angles 35 and 36 are secured tightly to the ends of the bars by through bolts 37. Since the angles 35 and 36 are the common steel angles having a fillet in the corner, they are further secured to the bar magnets through bakelite or other non-magnetic material spacers 38. The effect of these angles is that they constitute pole pieces providing a continuous south pole on one side of the carriage and a continuous north pole on the opposite side of the carriage.

Slidably mounted in the carriage 30 by means of the rods 39, sliding in sleeves 40 shown in Figure 7, there are two bars 41 preferably of non-magnetic material and having their faces substantially in the plane of the bottom sides of the angles 35 and 36. The relation of these bars to the pan shown in dotted lines is indicated most clearly in Figure 6.

Secured to the bars 41 at the center of the carriage there are uprights 42 to which are secured rollers 43. These rollers operate in a cam track 44 secured by frame structure 45 to the main track 33. A section of the cam track 44 is curved downwardly as indicated at 46 in Figure 5. When the carriage has reached the point at which the rollers 43 engage the section 46 on the track, the bars 41 will be pushed downwardly to force the supported article from the field of force of the magnets.

The cam track 44 may be continuous or may exist only in short sections at points at which the articles are to be released. In such instance, means will be provided to hold the bars 41 in their uppermost position. For example, the bars may be held up by springs or by friction means between the rods 39 and the tubes 40.

It will be obvious that many changes may be made within the scope of the invention. For example, instead of having a mechanical release mechanism in the form of the device shown in Figures 4 through 7, short-circuiting bar magnets may be used in a manner like that in which the releasing horse-shoe magnets are used in the device shown in Figures 1 to 3 inclusive. Likewise, a mechanical releasing mechanism could be utilized in connection with the horse-shoe magnets.

It will be seen therefore that I have provided a conveyor and particularly a magnetic carrier

or conveyor-carriage which is obnoxious to none of the objections applicable to electro-magnetic devices for the like purposes.

I claim:

- 5 1. In a conveyor, a track, a carriage for travel on said track, permanent magnets on said carriage for supporting articles of a magnetic material, short-circuiting means for said magnets carried on said carriage and movable with respect to said magnets selectively to short-circuit said magnets, and means on said track for moving said short-circuiting means selectively into and out of short-circuiting engagement with said magnets.
- 10 15. 2. A conveyor for articles of magnetic material comprising a carriage, means for moving said carriage over a path, a permanent magnet on said carriage having unlike poles for engaging a magnetizable article on said carriage to retain an article on the carriage, a magnetic conductor on said carriage and movable thereon between a first position in which said conductor is engaged with said magnet to provide a path about said poles while the latter are engaged with an article to diminish the field applied to said article and a second position wherein said conductor is disengaged from said poles, and means provided in the path of said movement of said carriage at a predetermined point therein for moving said magnetic conductor selectively into and out of engagement with said poles.
- 20 3. A conveyor for articles of magnetic material comprising a conveyor moveable over a path, a carriage on said conveyor, a permanent magnet on said carriage for supporting an article in a position in which the article depends from the magnet, a magnetic conductor supported on the carriage and moveable thereon between a first position in which said conductor is engaged with said magnet to short-circuit the magnet and reduce flux applied to the article and a second position wherein the conductor is disengaged from said magnet, and means provided in the path of movement of said carriage over said path by said conveyor and engaged during traverse of the conveyor for moving the conductor into and out of magnet short-circuiting engagement at a predetermined point in said path.
- 25 30 40 45
